CIGARETTE LIGHTER

Seymour Rappoport, 6 Rohallion Drive,
Runson, N.J. 07760

Original design application July 27, 1966, Ser. No. 3,232,
now Patent No. 209,319, dated Nov. 21, 1967. Divided
and this application Aug. 25, 1967, Ser. No. 10,734

Term of patent 14 years

Int. Cl. D27—05

U.S. Cl. D48—27

FIG. 1 is a perspective view showing a cigarette lighter of my new design.

FIG. 2 is a top plan view.

FIG. 3 is a side elevational view.

FIG. 4 is a front elevational view taken in the direction of the FIG. 5 arrow shown in FIG. 2.

FIG. 5 is a rear elevational view taken in the direction of the FIG. 5 arrow shown in FIG. 2.

The dominant features of my design reside in the portions shown in full lines.

This application is a division of my copending application Ser. No. D3,232, filed July 27, 1966 now Patent No. D209,319 granted Nov. 21, 1967.

I claim:

The ornamental design for a cigarette lighter, substantially as shown and described.
